DISPENSING PACKAGE

Fred C. Gluck and Perry A. McCaskey, Minerva,
Ohio, assignors to Minerva Wax Paper Company,
Minerva, Ohio, a corporation of Ohio

Application March 29, 1932. Serial No. 601,782

2 Claims. (CL. 206—58)

This invention relates to a dispensing package and a method of making the same.

The principal object of the invention is to provide an extremely simple and cheap dispensing package which shall be efficient for its intended purpose, convenient and sanitary. A more limited object is to provide a dispensing package which shall be comprised entirely of a roll of waxed paper or the like, a spiral cover therefor and simple means for holding said cover tightly against said roll from the time it is applied thereto until the beginning of use. A further object is to provide a method of making the package hereinafter described which shall render possible the accomplishment of the above mentioned objects.

We attain the foregoing and other and more limited objects in and through the construction and arrangement and the method hereinafter described and claimed and illustrated in the accompanying drawings in which Fig. 1 is a perspective view of a sheet of cardboard or the like from which the cover is made; Fig. 2 is a schematic showing of a vat with the cover being sized or soaked in accordance with the method; Fig. 3 is a cross sectional view through the completed package; Fig. 4 is a schematic elevational view showing the comparative size of the cover member, during the "forming" step, and the roll of wax paper to which it is to be applied; Fig. 5 is a view showing one form of my invention in side elevation; Fig. 6 is a left end view thereof; Fig. 7 is a right end view thereof; and Figs. 8 and 9 are side and end elevations of a modified form, Fig. 8 being fragmentary.

Referring now to the accompanying drawings, the numeral 10 indicates a cover member composed of cardboard or any other suitable sheet material. The cover 10 together with the roll 11 of waxed paper or the like about which it is closely wrapped, together with one or more rubber bands 12 constitute the dispensing package of my invention. For the convenience of the user, the extreme end 11^a of the waxed paper constituting the roll 11 extends between the overlapping portions 10^a and 10^b of the cover 10. As indicated in the drawing, the cover will be of such dimensions with respect to those of the roll 11 as to extend about 1½ times around such roll. It will be understood that a greater or less amount of overlapping of the parts 10^a and 10^b may be selected according to choice. If desired, a supporting core may be employed within the roll 11 for preventing collapse of the same. It is to be understood that the cover 10 will have a dimen-

sion in the direction of the axis of the roll somewhat greater than the length of such roll whereby to prevent contact of the waxed paper with insanitary objects.

As indicated in Fig. 5, the excess of length of the cover member 10 over that of the roll 11 may be from one-half inch to one inch at each end. The use of this excess length combined with a gripping action between the convolutions of the cover member brought about by the "forming" step hereinafter described, results in adequate protection of the end of the roll 11 against contamination. A further safeguard may be provided by using struck out tongues as indicated at 14 and 15 in Fig. 5. It is to be understood that tabs either of the type 14 or 15 may be employed at both ends of the roll if desired.

In the modification of Fig. 8, I have illustrated the use with a roll such as illustrated in Fig. 5, omitting the elongated ends, of a metallic cutting strip 16 attached to the outer edge of the cover member and provided with turned down extensions 17 at the ends. The portions 17 act as stops to prevent the roll from slipping out or partially out of the cover member. In this form, the cover member will preferably be somewhat longer than the roll, although not as much longer as in the case of the modification of Fig. 5.

In making up the dispensing package shown in Fig. 3, we first wet a sheet of cardboard or similar material, cut to the proper size, in water or a sizing solution contained in a vat 13, and then wind the same around the roll of waxed paper in the manner illustrated, and then apply one or more rubber bands or similar ties to hold the cover against the roll. The package so formed is then allowed to dry, after which it is ready for storage, transportation or use. The printing of any suitable advertising matter on the cover 10 may be accomplished before the same is immersed in the water or sizing solution or after the package has been formed and allowed to dry. In the former case, regard must be had to the kind of printing ink used in order that the appearance may not be affected by the water or sizing solution in the vat 13. While it has been found satisfactory in practice to wet the cover member 10 with water, we may also employ any suitable sizing solution, such as a dilute solution of glue. The characteristics of such solution must be such as to have the effect of rendering the cardboard or similar material plastic. That is to say, it must affect the cover member so that when the same is bent or curved, it has little or no tendency to return to original position; and by the

term "wet" as used in this specification is meant production of this effect. Where a sizing solution is used, the cover member will not only be impregnated with size, but will also be coated therewith whereby to render the surface smooth. This will avoid the necessity of using a cover member having a preformed smooth surface as would be desirable if water alone were employed or the cover were formed in some other manner. While it is not essential that the paper be coated where water alone is used, better results will be obtained thereby.

It is within the contemplation of our invention to wind the wet cover member independently of the roll which it is to cover and to a smaller size than such roll whereby it will have to be flexed to larger than its normal size when it is applied to the roll. This we term "forming" the cover member. This may take the form of winding the wet cover member on a separate mandrel and allowing it to dry, after which it may be applied to the cover either with the edge of the cover projecting between the overlapping portions of the convolutions thereof, as shown in Fig. 3, or simply wound around the roll, leaving the user to "thread" the wax paper or the like between the overlapping portions of the cover. In this case the ties may be omitted, although it is preferable to use them as a protection against endwise motion of the roll with respect to the cover during shipment.

When the sizing solution such as dilute glue is employed the cover member may be simply brought into contact with the surface of the solution as by being allowed to float thereon in which case only one side of the cover will be impregnated or coated. It may then be allowed to dry partially before the forming step. When the drying has progressed to the correct stage, it becomes possible to wind the cover upon a roll of waxed paper without its sticking thereto. This is true whether the end of the wax paper is threaded between the convolutions or not. In this case the "forming" is carried out in connection with the roll to be covered and no additional step is necessary. We prefer also to use the partial drying

method even though the cover is formed independently of and to a smaller size than the roll in connection with which it is to be used.

By the described processes we are able to produce a dispensing package which is satisfactory for waxed paper, the same consisting of the material to be dispensed, one rectangular sheet of cardboard and, temporarily, a pair of rubber bands. In some cases, it may be desirable, instead of using rubber bands, to wrap the package in paper, cellophane or the like, and rely upon such wrapping to act as the temporary means for holding the cover closely wound about the roll of waxed paper. In case paper is employed and a sizing solution is used in the vat 13, such paper may be printed with the desired advertising matter and simply torn or cut along the exposed edge of the cover 10 and from the ends of the package. In such case, the size will cause such wrapper to adhere to the outer surface of the cover 10 and form a permanent part thereof whereby the advertising matter will be displayed as long as the package is in use.

Having thus described our invention, what we claim is:

1. In combination with a roll of paper, a container therefor comprising a cover wound thereabout and having overlapping end portions, the web of paper from the roll passing outwardly between said end portions, said cover being inherently stiff and resilient and tending normally to maintain at all times a contracted relationship about said roll.
2. In combination with a roll of paper, a container therefor comprising a cover wound thereabout and tending inherently to maintain at all times a position surrounding said roll protecting the same from exposure with one end of the cover provided with a paper cutting edge and overlapping the other end of the cover whereby the paper web from the roll may be withdrawn outwardly between said ends and severed against said cutting edge.

FRED C. GLUCK.
